BEVERAGE COOLING DEVICE

Felix Kurpiewski, Trenton, N. J., assignor to The
K and R Manufacturing Company, a corpora-
tion of New Jersey

Application February 2, 1938, Serial No. 188,380

4 Claims. (CL. 62—128)

This invention relates to a beverage cooling device of the character set forth in my copending application filed July 12, 1937, Serial No. 152,273, and has for the primary object the provision of a power driven means for the positive circulation of the cooling fluid of the device and including means whereby the cooling fluid will be caused to circulate in a selected path with relation to the chilling coils of a refrigerating device to aid in the removal of frost and ice formation from the chilling coils and thereby assure a more efficient chilling of the cooling liquid employed for the chilling of the beverage and the purified air under pressure used for the expulsion of the beverage.

With these and other objects in view, this invention consists in certain novel features of construction, combination and arrangement of parts to be hereinafter more fully described and claimed.

For a complete understanding of my invention, reference is to be had to the following description and accompanying drawing, in which

Figure 1 is a fragmentary vertical sectional view illustrating a beverage cooling and dispensing device constructed in accordance with the present invention.

Figure 2 is a fragmentary sectional view illustrating a portion of the flume which receives portions of the chilling coil and acts in the directing of the cooling fluid in a selected path.

Referring in detail to the drawing, the numeral 1 indicates a tank substantially filled with a cooling liquid 2 and having a removable cover 3 and located on supporting legs 4. Chilling coils 5 are arranged in the container 1 immersed in the liquid 2 and form part of a mechanical refrigerating system (not shown) wherein the leads of the chilling coils are indicated by the character 6 and are shown extending through certain walls of the container. Arranged within the container 1 and within and spaced from the chilling coils 5 are beverage cooling coils 7, the outlet leads 8 thereof being shown extending through a wall of the container and provided with faucets 9. The inlet leads 10 of the beverage cooling coils 7 connect with taps 11 and the latter are adapted to beverage containers 12. The taps 11 are also connected to an air pressure manifold 13 by pipes 14, control valves 15 being provided in the pipes 14. An air filter 16 of the liquid type is located in the container 1 and immersed in the cooling liquid 2 and has connected thereto an air pressure supply pipe 17 and an outlet pipe 18 connected with mani-

fold 13 so that purified and cooled air under pressure will be delivered to the manifold 13 and thence to the contents of the beverage containers 12 for placing the beverage under pressure to be expelled through the chilling coils 7 when the faucets 9 are opened. While the drawing shows the air filter in a certain location in the container 1 it is to be understood that it may have other selected positions.

To bring about a circulation of the cooling fluid 2 in the container 1 a circulating power driven pump 18' is provided, the inlet pipe being indicated by the character 19 and the outlet pipe by the character 20 both of which extend into the cooling liquid. The outlet pipe 20 terminates in a trough or flume 21 arranged on the bottom of the container 1 and which has therein several convolutions of the chilling coils, as shown in Figure 2, so that the cooling liquid forced by the pump 18' passes through the trough rapidly contacting the chilling coils and then circulating completely about within the container 1 which brings about a thorough cooling of the cooling fluid which in turn cools the beverage coils 7 and their contents as well as cooling the air under pressure passing through the filter and further aids in removing frost and ice formations from the chilling coils.

It is to be understood that some other means than that heretofore described and shown in the drawing may be employed for the circulation of the cooling fluid 2 and still obtain the desired results by this device.

What is claimed is:

1. A beverage dispensing device comprising a container having therein a cooling liquid, chilling coils of a refrigerating device immersed in said liquid, beverage dispensing coils immersed in said liquid, means including taps for connecting said dispensing coils to beverage receptacles, control faucets connected to said beverage dispensing coils and arranged exteriorly of said container, means connecting said taps to an air pressure supply, a trough arranged in the container and immersed in the liquid with certain convolutions of the chilling coils therein, and means for agitating the liquid in the trough.

2. A beverage dispensing device comprising a container having therein a cooling liquid, chilling coils of a refrigerating device immersed in said liquid, beverage dispensing coils immersed in said liquid, means for connecting said beverage dispensing coils to beverage receptacles, control faucets connected to said beverage dispensing coils and arranged exteriorly of the container, air

purifying means immersed in said liquid, means connecting said purifier to an air pressure supply, means connecting said purifier to said beverage receptacles, a trough arranged in the container and immersed in the liquid with certain convolutions of the chilling coils therein, and a power driven pump including inlet and outlet pipes extending into the container and the liquid thereof with the outlet pipe terminating in the trough.

3. A beverage dispensing device, comprising, a container having therein a cooling liquid, chilling coils of a refrigerating device immersed in said liquid, beverage dispensing coils immersed in said liquid, means including taps for connecting said dispensing coils to beverage receptacles, control faucets connected to said dispensing coils and arranged without said container, means connecting said taps to a purified air pressure sup-

ply within said container, a trough arranged in the container and immersed in the liquid with certain convolutions of the chilling coils therein, and a power driven pump including inlet and outlet pipes extending into the container and the liquid thereof with the outlet pipe terminating in the trough for agitating the liquid therein.

4. A device of the character described, comprising, a container having therein a cooling liquid, a beverage cooling coil within said container, a refrigerant coil within said container, an air purifier within said container, a trough in said container and immersed in said cooling liquid with certain of the convolutions of the refrigerant coil therein, and a pressure conduit extending into said container and terminating in the trough for agitating the liquid therein.

FELIX KURPIEWSKI.
